Primary Examiner—Janice Seeger*(74) Attorney, Agent, or Firm*—Warner Norcross & Judd LLC(57) **CLAIM**

The ornamental design for a work station, as shown and described.

DESCRIPTION

FIG. 1 is a perspective view of the work station;

FIG. 2 is a top plan view thereof;

FIG. 3 is a bottom plan view thereof;

FIG. 4 is a left side elevation view thereof;

FIG. 5 is a front elevation view thereof;

FIG. 6 is a right side elevation view thereof; and,

FIG. 7 is a back elevation thereof.

The phantom lines are for illustrative purposes and form no part of the claimed design.

The broken lines are for illustrative purposes only and form no part of the claimed design.
